[57] **CLAIM**

The ornamental design for a golf ball washer enclosure, as shown and described.

DESCRIPTION

FIG. 1 is a perspective view of a golf ball washer enclosure showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The golf ball washer, wastebasket, logo and hole indicia are shown in broken lines in FIGS. 1-6 for illustrative purposes only and form no part of the claimed design.

FIG. 1

FIG. 2

FIG. 3

FIG. 4

FIG. 5

FIG. 6

FIG. 7
